SIGNALING APPARATUS

Victor E. Carbonara, Rockville Centre, N. Y., assignor to Bendix Aviation Corporation, South Bend, Ind., a corporation of Delaware

Application September 28, 1932, Serial No. 635,254

9 Claims. (Cl. 177—337)

The present invention relates to signaling devices adapted to transmit and receive signals to and from a remote station, and more particularly to devices of the type generally known as ship's telegraphs.

One of the objects of the present invention is to provide a novel structure whereby a double signaling unit of the above referred to type operable from either end thereof is rendered possible.

Another object is to provide a novel construction of a device of the foregoing character capable of controlling the motion of a similar remotely disposed but related device, and at the same time capable of responding to movements imparted to the same or another remotely disposed but related device.

Devices of the class described have heretofore embodied rotatable elements mounted in a frame or casing through which the shaft of such rotatable element extends to provide means for connecting a suitable pointer or operating handle thereto, in conjunction with a dial having inscribed thereon suitable reference characters or indicia to guide the operator and indicate the signals to be transmitted and/or received. Where the location of such devices has permitted, the operating handle has been mechanically connected to the rotatable member at the rear of the casing of the device, as indicated, for example, in Fig. 2 of the patent to Frank W. Wood No. 1,562,483 or in Fig. 3 of the patent to Lloyd E. O'Neal and Samuel N. Mead, Jr. No. 1,693,663, thereby avoiding the necessity of puncturing the front cover-plate of the device, which cover-plate is usually of glass so that the indicia on the dial may be visible therethrough. In many instances, however, the locations in which such devices are used, particularly in engine rooms of ships, render the rear of the signaling unit inaccessible for attachment of the operating means and in such instances it has been necessary to puncture the cover-glass or cover-plate with a resulting weakening of such member thereby subjecting it to the risk of breakage.

The present invention eliminates the foregoing difficulties and permits the combining, in a novel manner, of two signaling units by providing a novel structure whereby the operating handle may be attached at the forward portion of the unit in all cases regardless of positions or locations of the support to which the unit is attached when a single unit is employed, and without causing interference between the operating handles when two such units are combined, and whereby the

necessity of any part of the unit having to pass through the cover-glass or plate is eliminated.

Another object of the invention is to provide a novel construction in a signal transmitting and/or receiving unit of the class described in which a portion of the casing, including the front cover-plate, is rotatable about a stationary dial plate on which orders to be transmitted as well as those to be received are indicated by the rotation of an index member secured to or formed integral with such outer casing and hence rotatable about such dial plate, and by a second index member or pointer, respectively, the latter being operated by the receiving element of the signaling unit.

Still another object is to provide a novel structure in a signaling unit of the foregoing type whereby a double-faced instrument may be formed by combining two single units into a unitary construction embodying two pairs of relatively rotatable transmitters and receivers enclosed in the same casing and permitting relative rotation therebetween throughout 360° and in which the operating handles of the units are in planes parallel to the dial plates so that their relative angular positions in those planes afford, at a glance, a rough indication of the signal transmitted thereby.

A still further object of the invention is to provide in a unitary structure, a light, compact and novel arrangement of a plurality of relatively rotatable transmitters and receivers for the purposes described.

The above and other objects and advantages of the invention herein disclosed will become more fully apparent from a consideration of the detailed description which follows when read with reference to the accompanying drawings wherein two embodiments of the invention are illustrated. It is to be expressly understood, however, that the drawings are for the purpose of illustration only and are not to be construed as a definition of the limits of the invention, reference being had for this purpose to the appended claims.

In the drawings wherein like reference characters refer to like parts in the related views,

Fig. 1 is a central longitudinal section through a casing in which are supported two similar devices each of which embodies the present invention, one of the devices being shown in elevation and the other in longitudinal section;

Fig. 2 is a section similar to that shown in Fig. 1 of another embodiment of the invention;

Fig. 3 is an electrical circuit diagram showing the connections involved in the application of

the embodiment of the invention shown in Fig. 1 to the sending and receiving of signals to and from a remote station; and

Fig. 4 is another electrical circuit diagram showing the connections of two units of the type shown in Fig. 2.

In the two embodiments herein illustrated and described in detail, the invention is shown in Fig. 1 applied to a pair of signaling units of the type disclosed in the copending application, Serial No. 530,099 filed April 14, 1931, for Dynamo electric machines, and in which each unit is provided with two or more rotatable armatures one of which functions as a generator capable of actuating a system of self-synchronous motors to transmit signals to each of such motors and the other armature of each unit functioning as a self-synchronous motor adapted to respond to the movement of a signal-transmitting generator electrically connected thereto; while in Fig. 2 the invention is shown applied to a pair of signaling units of the type in which each unit is provided with a stationary indicating unit having a movable pointer and with two relatively rotatable members, the operation of which is adapted to vary the resistance of an electrical circuit to produce an indication at a remote point, the indicating unit in turn being adapted to be operated by a similar transmitting unit at the remote point; but it is to be understood that the invention is equally adaptable to any other known type of signaling unit, whether mechanical, electrical or electro-mechanical, capable of transmitting and receiving signals to and from a remote station.

Referring now to the drawings and more particularly to the embodiment shown in Fig. 1, the invention is shown applied to a signaling unit of the type disclosed in the above referred to application, Serial No. 530,099 wherein are provided two armatures having a common field, said armatures and field being individually relatively rotatable with respect to each other and adapted to be connected to the armatures and field of a signaling unit located at a remote point. The fields of the two units are arranged to be energized so that a fixed phase relation is established among the fluxes of the armatures and field of each unit so that upon disturbance of the flux relation among the armatures and fields of one unit, by relative rotation therebetween, a disturbance is produced in the flux relation among the corresponding armatures and field of the other unit, thereby causing relative rotation among the armatures and field of the latter unit, and vice versa. In accordance with the present invention, however, two units are provided at both the transmitting and receiving ends of the system, said units being mounted back to back to constitute a unitary double-faced signaling device whereby indications may be observed from either side of said device. Since the units are of similar construction the description of the one shown in section in Fig. 1 will be sufficient for a complete understanding of the invention.

In the form shown, the two units are mounted in a cylindrical housing 5 which may be secured to or formed integral with a transversely projecting portion 6 adapted to be secured to a supporting bracket 7 in any suitable manner as by means of screws 8. The two units are supported within the cylindrical housing 5 preferably by means of a common supporting web 9 or a transverse wall formed integrally with and on the interior of said housing and having a coaxial hub, although any other suitable support may be provided for the

units as will be readily apparent to those skilled in the art. Each unit comprises, as shown, armatures 10 and 11 having interposed therebetween and preferably concentric therewith a common field 12, said armatures, in the present instance, being rotatable while the field remains stationary so that they thus constitute rotors and a stator, respectively. If desired, however, either one or both of the armatures could be stationary and the field rotatable.

The armature 10 is of the physical form usually employed in direct current dynamo electric machines but has three windings 10a (Fig. 3) connected together in "delta" arrangement for alternating current operation and is provided with a shaft 13 on which are wound the coils 10a and which is journaled at both ends in suitable bearings such as ball-bearings 14 and 15 carried by a hub 16 and a plate 17, respectively. The hub 16 is preferably formed integrally with a bowl-shaped member 18 which constitutes the supporting structure of the stationary field 12 and is, therefore, fixed to the web 9 in any suitable manner as by means of a pin 19 which passes through a tubular extension 20 of the bowl-shaped member 18, said tubular extension 20 constituting a shaft and being supported in and extending through a hub 21 formed integrally with the web 9 so that a similar structure may be provided at the other end of the extension to constitute the other unit shown at the right of Fig. 1. The plate 17 is made stationary and, therefore, secured to an annular member 22, as by means of screws 23, which forms part of the bowl-shaped casting 18, the latter also having an internal annular flange 24 which carries an annular laminated core 25 of the field 12, and wound around said core is a field winding 26.

Suitable means are provided for supplying current to the armature 10 and in the form shown comprise a set of stationary brushes 27 which cooperates with a set of collector rings 28 mounted on and rotatable with the shaft 13 of said armature. The brushes 27 are mounted on a bracket 29 carried by the fixed casting 18. The armature 10, in the present embodiment, is the receiving element of the signaling unit and is adapted to be actuated when current flows through the windings thereof due to a disturbance in the flux relation between another armature and field located at the remote station.

The armature 11 is constituted by a "delta" winding 30 wound on an annular laminated core 31 carried in a rotatable housing 32 composed of two sections 33 and 34 secured together in any suitable manner as by means of screws 35. The section 34 of the rotatable housing 32, is journaled on the tubular extension 20 of the fixed casting 18 in any suitable manner as, for example, by means of a bushing 36 threaded within a hub 37 formed integral with the section 34 which is of a contour similar to the bowl-shaped stationary member 18. The forward end of the section 33 terminates in an enlarged portion 38 within which the indicating elements are adapted to be viewed through a cover-glass 39 provided at the open end of the portion 38 and held in position therein as by means of a flange 40 and a clamping ring 41. An auxiliary housing 42 adapted to project within the section 33 is secured to the latter as by means of screws 43 and within which are carried internal collector rings 44 cooperating with brushes 45 to supply current to the winding 30 of the armature 11, said brushes being mounted on a bracket 46 also carried by or forming part of

the stationary member 18. The auxiliary housing 42 has formed integral therewith a hub 41 which together with the annular member 22 constitutes a journal for the other end of the rotatable casing 32.

The casing 32 and, hence, its enlarged portion 38 is adapted to be rotated about the fixed casing 18 by means of an operating handle 48 secured to or formed integral with the enlarged portion 10 38 thereby causing rotation of the armature 11 with respect to the stationary field 12 and disturbing the flux relation therebetween to cause a signal to be transmitted to the remote station by causing current to flow in an armature similar 15 to the armature 10 located at said remote station. On the enlarged portion 38 there is also provided a suitable rearwardly extending fork 49 adapted to engage and restrain an arm 50 pivoted to handle 48 as indicated at 51, the arm 50 being 20 in turn adapted to be restrained by frictional engagement with an annular disc 52 secured to a flange 53 on the housing 5 by screws 54, thereby providing a friction brake between the rotatable housing 32 and the stationary housing 5. The 25 arm 50 is normally in engagement with the annular disc 52 until disengaged by moving the lever 55 against the compression of a spring 56 seated within the handle member 48 when the latter is grasped for operation. If desired, the annular disc 52 may be provided with peripheral notches 30 into which the arm 50 may be forced by the spring 56 when the handle 48 is released.

Means are now provided whereby, upon the transmission of a signal to a remote station by the 35 rotation of the housing 32 through the medium of the handle 48 and/or upon the reception of signals from said remote station by the actuation of the rotor 10, such signals may be indicated and, in the form shown, comprise an index member 57 secured to or formed integral with and on the interior of the enlarged portion 38, and a second index member 58 mounted on the outer end of the shaft 13 of the armature 10, said index members 57 and 58 cooperating with a fixed 40 dial 59 having suitable reference characters thereon. The dial is held stationary by mounting the same on the fixed plate 17 in any suitable manner as by means of rivets or screws 60 adapted to engage with bosses 61 provided on said fixed 45 plate 17.

It will be seen from the foregoing that if two devices of the character of which one is shown in section in Fig. 1 are electrically connected together, as indicated in the circuit diagram of Fig. 55 3, with their stationary fields in parallel with a suitable source of alternating current through a supply switch 62, and the two sets of brushes 27 and 45 of the rotors 10 and 11 connected to corresponding sets of brushes of the other rotors, 60 the angular movements of the rotor 11 at the transmitting end will cause a corresponding equal angular movement of a rotor 10' at the receiving end and conversely the rotor 10 will be caused to rotate when the rotor 11' at the other end is actuated. If the rotor 11 at the transmitting end 65 is rotated at a constant speed, the associated rotor 10' at the receiving end will rotate at the same speed but will lag rotor 11 by such an angle that the torque developed will be sufficient to overcome any frictional and wind losses. As soon as 70 rotor 11 is decelerated and brought to rest the connected rotor 10' will decelerate at the same rate and come to rest in synchronism therewith. It will also be apparent, as pointed out in the 75 above referred to copending application, that the

rotor 10 may be made to constitute the transmitting rotor and the rotor 11 as the receiving rotor if so desired, but for the purpose of the present invention the arrangement is preferably such, as shown in Fig. 1, that the outer rotor be employed as the transmitting rotor in order to attain the objects desired, namely, avoiding the necessity of puncturing the cover-glass 39 for the purpose of connecting an operating handle to the rotor 10.

The unit shown in elevation at the right of Fig. 1 is, as hereinbefore stated, identical with the unit shown at the left in section and is electrically connected to a similar unit located at the remote station with which it is desired to exchange signals, but enclosing and supporting the two units within a common stationary casing, such as the casing 5, affords ready operation of the unit from either side thereof and also provides indications from two sides of the unit, these features being possible only by virtue of the fact that two units can be combined into a unitary structure because the operating handle 48 forms part of the rotatable casing instead of being provided at the rear of each unit as has been done heretofore.

Referring now to Fig. 2, there is shown another embodiment of the invention where the same is applied to a pair of signalling units of the type in which each unit is provided with a stationary indicating unit having a movable pointer and with two relatively rotatable members, the operation of which is adapted to vary the resistance of an electrical circuit such, for example, as a Wheatstone bridge to provide an indication at a remote station, the indicating unit in turn being adapted to be operated by a similar transmitting unit at said remote station. In the form shown, each unit as illustrated in section at the left, comprises, as in Fig. 1, a rotatable housing or casing 63 journaled within a stationary cylindrical casing 64 carried by a suitable supporting standard 65 and secured to the latter as by means of screws 66. The housing 63 has a cylindrical portion 67 which projects within the casing 64 and an outer enlarged flared portion 68 to which is secured an operating handle 69 for rotating said casing 63 for the purpose of transmitting a signal. The casing 63 is journaled on a hollow stationary shaft 70 which is keyed to and extends through a hub 71 provided on an annular web or wall 72 formed integral with the stationary casing 64, said hollow shaft extending through the cylindrical portion 67 of the casing 63 and having keyed thereto at its left end a smaller housing 73 within which is secured a receiving element 74 as by means of screws 75. A similar pair of housings (not shown) are keyed to the right end of the shaft 70 to form the structure of the second unit within the fixed housing 64. The transmitting element 60 of the present embodiment comprises a box 76 secured to and rotatable with the cylindrical portion of the rotatable casing 63, the securing means being shown as screws 77. Within the box 76 is an annular member 78 having a circular cross-section and on which is wound a suitable resistor 79, said annular member being secured to the hollow shaft 70 in any suitable manner (not shown), the box 76 being, for this purpose, so constructed that the shaft 70 passes therethrough. Cooperating with the resistor 79 is a sliding contactor 80 carried by a bracket 81 secured to the box 76 and by means of a screw 82, said contactor being in continuous electrical contact with the resistor 79 and adapted, upon 75

rotation thereof with the casing 63 due to the fact that the box 76 is secured to said casing, to cut in or cut out any desired amount of the resistor 79 for the purpose of unbalancing a 5 Wheatstone bridge circuit, as will appear more fully hereinafter with reference to Fig. 4 to actuate a receiving element 74' which is the same as the element 74 but located at a remote station. The receiving elements 74 and 74' may be any 10 suitable type of electric meter adapted to be actuated in response to and in accordance with variations in electric current, and is provided with a pointer 83 which cooperates with a fixed dial plate 84 secured to the casing 73 as by screws 15 85, said dial 84 having appropriate reference characters thereon for indicating the signals desired to be transmitted and/or received. Another index member or pointer 86, similar to the index member 57 shown in Fig. 1, is secured to and 20 rotatable with the casing 63 on the interior of the enlarged flared portion 68 and arranged to traverse the dial 84 upon rotation of said casing 63. A cover-glass 87 is also provided through which the index members 83 and 86 and dial 84 25 may be viewed.

If two devices of the type shown in Fig. 2 are associated with each other, as shown in a circuit diagram in Fig. 4, with the resistor 79 having its ends connected to two other resistors 88 and 89, 30 respectively, at the points 90 and 91, and the ends of the resistors 88 and 89 connected together at the point 92 and then connecting the points 90 and 91 to a suitable source of current to form a Wheatstone bridge, one arm of which is constituted by 35 the resistor 88 and the portion 93 of the resistor 79, and the other arm of the bridge being constituted by the resistor 89 and the portion 94 of the resistor 79, the one device will produce an unbalance of the bridge when the contactor 80 40 is rotated to cause current to flow in the electric meter 74' located at the receiving end, said meter being connected to the contactor 80 and the point 92. Similarly when the contactor 80' is operated at the other end it will produce an unbalance of 45 the associated Wheatstone bridge circuit to cause current to flow through the electric meter 74 located at the first end.

There is thus provided a novel signaling device adapted to transmit and receive signals to 50 and from a remote station and embodying a novel construction whereby two such devices may be readily combined into a single unit operable from either side thereof, and whereby the necessity of any part of the unit having to pass through 55 the cover-glass or plate thereof is eliminated. There is also provided a novel structure whereby a signaling unit embodying the same may be mounted in any location, particularly where space is limited and the unit must necessarily be 60 mounted on a wall or bulkhead, without having to break through any part of the casing to provide means for operating the transmitting elements thereof.

While the invention is of decided practical 65 merit when applied to electrical systems of the type described and disclosed herein, it is to be expressly understood, however, that these systems are merely illustrative of any suitable driving or controlling mechanism which may be used 70 in place of the controlling mechanisms shown in Figs. 1 and 2. Thus, for example, although it is usually desirable for various reasons to provide electrical or at least electrically controlled mechanisms, of which the present instrumentalities are representative in a broad sense, it is contem-

plated that in certain instances mechanical or pneumatic driving means may be substituted therefor. Moreover, the control may be effected through suitable inter-relation of other electrical, 5 mechanical, or electro-mechanical equivalents.

Likewise, the construction of the device shown in Figs. 1 and 2 may be varied within the limits of the broad inventive concept herein disclosed without departing from the scope of the invention as intended to be defined within the appended 10 claims. Thus, for example, indications may be given by means of electrically actuated index elements or pointers movable in paths other than the circular paths indicated, it being understood that in such cases suitable connections for operating 15 said index elements may be substituted for the connections indicated in Figs. 3 and 4.

It is also to be understood that various other changes and modifications, which will now appear to those skilled in the art, may be made in the 20 construction, arrangement and inter-relation of the parts constituting the invention without departing from the spirit thereof. Reference will, therefore, be had to the appended claims for a 25 definition of the limits of the invention.

What is claimed is:

1. In a signaling device for transmitting and receiving signals to and from a remote station, the combination of a rotatable casing and fixed supporting means therefor, a stationary dial 30 within said casing and secured to said fixed supporting means, an index element secured to and movable with said casing and cooperating with said dial, a second index element journaled in said fixed supporting means and cooperating with 35 said dial independently of the first index, means for actuating said second index element in response to signals received from the remote station, and means associated with said rotatable casing and supporting means, respectively, to 40 cause transmission of signals to the remote station in response to rotation of said casing.

2. In a signaling device, the combination of a fixed support including a stationary casing secured thereto, a rotatable casing supported by 45 and journaled in said stationary casing, means associated with said two casings for causing transmission of signals to a remote station in response to the rotation of the rotatable casing, a rotatable member journaled in said fixed support axially of and within said rotatable casing, 50 means for actuating said member in response to signals received from the remote station, a fixed dial supported by the stationary casing, an index member secured to and rotatable with the rotatable casing and cooperating with said fixed dial to indicate the signals transmitted by the rotation of the casing, and a second index member 55 secured to and rotatable with said rotatable member and cooperating with the same dial to 60 indicate the signals received from the remote station.

3. In a device of the class described, a rotatable casing and fixed supporting means therefor, a stationary dial within said rotatable casing and 65 secured to said fixed supporting means, an index element secured to and rotatable with said rotatable casing and cooperating with said dial, and means associated with said rotatable casing and 70 said supporting means, respectively, to cause transmission of signals in response to rotation of said casing.

4. In a device of the class described, a rotatable casing and fixed supporting means therefor, a stationary dial within said rotatable casing 75

and secured to said fixed supporting means, an index element carried by and rotatable with said rotatable casing and cooperating with said dial, and electrical means associated with said rotatable casing and said supporting means, respectively, to cause transmission of signals in response to rotation of said casing.

5. In a device of the class described, a rotatable casing having a bearing hub at one end thereof, a fixed supporting means including a member passing through said hub and into said casing in coaxial relation therewith, a stationary dial secured to said fixed member, an index element secured to and rotatable with said casing and cooperating with said dial, and means associated with said rotatable casing and said supporting member, respectively, to cause transmission of signals in response to rotation of said casing.

6. In a device of the class described, a rotatable casing having a bearing hub at one end thereof, a fixed supporting means including a member passing through said hub and into said casing in coaxial relation therewith, a stationary dial secured to said fixed member, an index element secured to and rotatable with said casing and cooperating with said dial, and electrical means associated with said rotatable casing and said supporting member, respectively, to cause transmission of signals in response to rotation of said casing.

7. In a device of the class described, a rotatable casing and fixed supporting means therefor, a stationary dial within said rotatable casing and secured to means rigidly connected to said fixed supporting means, an index element secured to and rotatable with said rotatable casing, and

electro-magnetic means associated with said rotatable casing and said fixed supporting means, respectively, to cause transmission of signals in response to rotation of said casing.

8. In a device of the class described, a rotatable casing having a bearing hub at one end thereof, a fixed support including a member passing through said hub and into said casing in coaxial relation therewith, a stationary dial connected to said fixed member, an index element secured to and rotatable with said casing, and electro-magnetic means associated with said rotatable casing and said supporting member, respectively, to cause transmission of signals in response to rotation of said casing.

9. In combination, two rotatable casings having a common fixed support therefor including a common stationary casing partially enclosing said rotatable casings and each of said rotatable casings constituting a dynamo electric machine having two relatively rotatable armatures arranged in concentric relation and a fixed field interposed between said armatures also in concentric relation therewith, said field being secured to the fixed support, and one of said armatures being secured to and rotatable with its rotatable casing, and the other of said armatures being journaled in the fixed support, a stationary dial in each rotatable casing and also connected to the fixed support, and a pointer connected to each armature and cooperating with their associated dials to indicate, respectively, signals transmitted and received by relative rotation between the respective armatures and the associated field.

VICTOR E. CARBONARA.
